ELECTRIC LAMP

George E. Inman, East Cleveland, Ohio, assignor
to General Electric Company, a corporation
of New York

Application August 30, 1934, Serial No. 742,126

6 Claims. (Cl. 176—1)

This invention relates to electric lamps and the like, and particularly to vapor lamps such as the so-called low-pressure "positive column" type or the "cathodic glow" type, giving diffuse rather than sharply localized or intense concentrated luminosity. The invention is concerned with lamps that contain a vaporizable working substance, e. g., sodium and some other metals, and operate with very small vapor pressure of 5 such substance. In such lamps, the absolute vapor pressure of the working substance is usually about 1 or 2 microns for sodium. Vapor pressures of low order are characteristic of the typical diffuse glow discharge, that generally 10 appears to fill the whole lamp bulb.

Very usually, vapor lamps contain a small amount of easily ionized gas like neon, argon, etc., whose (partial) pressure in the lamp is around 1 or 2 to 7 mm., to assist in starting the 15 sodium or other vapor discharge. This is the more desirable in lamps using a difficultly vaporizable working substance like sodium, as contrasted with one that is much more easily vaporized like mercury.

Commercial sodium vapor lamps aim at operating temperatures around 250° C. for maximum efficiency; while the actual temperatures of their envelope or bulb walls range from about 220° C. or less to about 275° C. or more. The boiling 20 point of sodium being about 877° C., the sodium vapor in the commercial lamp bulb is continually condensing on its inner surface and vaporizing again, with a tendency to accumulate and remain in any region or area that is relatively 25 cool, because of the slower vaporization from the cooler region. This means that the sodium vapor pressure in the envelope will tend to fall below that corresponding to the general lamp temperature, and to approach that corresponding 30 to the lowest temperature: i. e., that the lamp will virtually lack sodium, and its light output and efficiency suffer correspondingly. Or if the attempt is made to remedy this by forcing the 35 lamp to operate at a higher current density in the glow discharge, and thus heat up its coolest region(s) to 250° C. or thereabout, then the general lamp temperature will be forced still higher, and the efficiency will also suffer.

Practically, it is very difficult to design a 40 commercial lamp of the diffuse arc discharge type containing difficultly vaporizing metal so as to be evenly heated by its arc discharge; and the variation in wall temperature is apt to be 45 even less favorable than the above-suggested

range of 220° C. to 275° C. in the sodium vapor lamp.

While an adequate though small vapor pressure of sodium or the like is essential to the operation of an arc discharge vapor lamp, and while the most favorable sodium pressure for efficiency is that corresponding to a (uniform) temperature of about 250° C., the current density in the discharge is also very important to the efficiency, and in a contrary sense: i. e., the lower 5 the current density, the greater the luminous efficiency of the discharge. However, discharge currents that would be highly favorable from this point of view are insufficient to heat the lamp to the temperature that is most favorable as 10 regards vapor pressure of a working substance such as sodium. This is so even when the sodium vapor lamp is operated in a double-walled vacuum jacket in order to conserve heat, as is 15 customary.

Other limitations and drawbacks of such vapor lamps have lain in the necessity of a ballast resistance in series with the lamp, to control and limit rise of current through the lamp as it heats up; and of either providing compensating 20 resistances, reactors, or transformers to allow such lamps to operate in parallel on ordinary (alternating current) lighting circuits of 110-120 volts, or else operating a plurality of the lamps in 25 series.

I have found that these difficulties can be overcome, and a very high operating efficiency realized in a lamp of this general type, by supplying additional heat as uniformly as possible and as nearly according to the deficiency in the 30 various parts of the lamp as possible, so as to maintain a proper uniform lamp temperature with a relatively low discharge current, or current density. Preferably, and as hereinafter described, the lamp is heated internally. Suitable 35 electrical heating means for this purpose may be operated independently, from a separate heating circuit, or may be adapted and used to ballast the lamp, or may be used to compensate for its low operating voltage. Useful light may be obtained from an incandescent body or filament thus employed, as well as heat; and the enhanced 40 luminous efficiency of the glow discharge will make up for relatively poor luminous efficiency of such a filament. With the improvement in 45 efficiency, I may combine improvement in quality of the light, compensating for color deficiency in the glow discharge, and even approximating a white light.

I also aim to make the vapor lamp a complete 50

operating unit in itself, without need of extrinsic accessories, such as external ballast, or resistances, reactors, or transformers. I have here particularly illustrated and described my invention as applied to lamps of cylindrical or tubular form; but while the cylindrical or tubular shape lends itself very advantageously to my purpose, it is not essential, and the invention in its broader aspects can be adapted to other shapes.

10 Various other features and advantages of the invention will appear from the following description of species thereof, and from the drawings.

15 In the drawings, Fig. 1 is a side view of one form of lamp embodying my invention, particularly adapted for operation on alternating current.

20 Fig. 2 shows a vertical section through one of the electrodes shown in Fig. 1, on a larger scale.

25 Fig. 3 shows a vertical section through the electrodes and a refractory insulative tube on which they are mounted—certain parts being broken out—and illustrates a modification.

30 Fig. 4 is a side view of another form of lamp embodying the invention.

35 Fig. 5 is a diagram of the electric circuits and connections of the lamp shown in Fig. 4.

40 Fig. 6 shows a vertical section through one of the electrodes shown in Fig. 4.

45 Fig. 7 is a side view of still another form of lamp embodying the invention.

50 Fig. 8 is a plan view of a spider at the top of the lamp mount of Fig. 7.

55 Fig. 9 is a fragmentary side view of the lower portion of the lamp mount of Fig. 7, taken at right angles to Fig. 7.

Fig. 10 is a diagram of the electric circuits and connections of the lamp shown in Fig. 7.

The lamp shown in Fig. 1 comprises an envelope or bulb 10 of elongated cylindrical or tubular form, with spherically rounded end(s), and a mount 11 sealed into the lower end of the envelope. Being equipped with an Edison screw base 12, this particular lamp has a reduced neck 13 on which the base is secured, and its mount 11 includes a tubular stem 14 sealed into the neck 13 within the base 12. Current leads 15, 16 are connected to the shell and center contacts of the base 12 and extend in through the stem 14, and are sealed in the press 17 at the inner (upper) end of the stem. In the stem 14 is also shown an exhaust tube 18 that opens into the bulb neck through the stem press 17 and is sealed off at its lower end, which is hidden by the base 12. Besides stem 14 and leads 15, 16 the mount 11 may include electrodes 20, 20 for the luminous glow discharge, and means for independently heating the envelope 10, as already mentioned.

The electrodes 20, 20 may be centrally arranged in the envelope or bulb 10, so that the discharge shall tend to heat the envelope 10 as evenly as possible. As shown, the upper electrode 20 is almost or entirely in the upper spherical end portion of the bulb 10, while the lower electrode 20 is partly in the lower spherical end portion and partly above it. These electrodes 20, 20 may be of either indirectly heated or directly heated electron-emissive types, such as known in the art.

70 The independent heating means for the envelope 10 should be symmetrically arranged therein as regards its heating effect, which generally means at as uniform distance as may be from the nearest envelope wall everywhere. In a tubular envelope 10, these principles are per-

haps best satisfied by a cylindrical or linear (electrical) heater extending coaxially with the envelope 10 between the electrodes 20, 20, as in Fig. 1. The actual heating device here shown is a resistance wire or filament 22 (of tungsten or other material of positive temperature-resistance coefficient) wound in a fine helix, and heated to bright incandescence by the current through it. This heating resistance 22 is preferably enclosed in an insulative refractory 5 tube 24, of beryllia or other suitable oxide (such as thoria, alumina, or magnesia), which may be heated to a low incandescence of visible redness by the filament, thus transforming the (brighter) radiation of the filament to 10 red. The tube 24 is also adapted to prevent a discharge between the filament 22 and one of the electrodes 20, 20 when there is considerable difference of potential between them, thus allowing the device to operate under a higher voltage 15 than might be practicable without it. The electrodes 20, 20 are mounted directly on the ends of the tube 24, preferably beyond the ends of the filament 22. The tube 24, which thus serves as a 20 principal supporting member for various operating parts, may be mounted on the stem 14 in any suitable way, as by inserting the upturned end of the irregularly Z-bent stem lead 15 in the lower end of the tube 24, and cementing it there, if desired. The upper end of the tubular member 24 may be steadied by attachment 25 or engagement at this end of the bulb 10, as around a (molybdenum) wire 25 fused into the bulb wall at 26, and cemented into the tube 24 if desired. The heating filament 22 may be 30 (electrically) connected and stretched between the end of lead 15 inside the tubular member 24 and the lower end of wire 25, which thus serves as a lead for the filament. In the present instance, the leads 15 and 25 extend into the tube 35 40 substantially all the way through the electrodes 20, 20, and the filament resistance 22 only occupies the portion of the tube 24 between the electrodes; but in the aggregate, this heating resistance with the electrodes extend axially 45 substantially or approximately from end to end of the main vapor space of the envelope 10, above the neck 13. The like is true of the "heater" broadly if regarded as coextensive with the tube 24, which diffuses the heat of the filament 50 lengthwise and radially throughout its own length.

The construction and mounting of the electrodes 20, 20 on the member 24 may be identically the same, and is shown for the upper electrode in 55 Fig. 2. This upper electrode 20 includes a heating resistance coil 30 wound helically on the member 24, and consisting of a (tungsten) filament itself coiled in a fine helix. To the ends of the heating resistance 30 are connected (molybdenum) current leads 31 and 32, which also make a couple of turns around the member 24. These resistance and lead coils are enclosed or embedded in a refractory insulative covering 33, which may be formed of a beryllia paste applied 60 as such and then baked on. Around the covering 33 is fixed a (nickel) tube 34, which is in turn coated with electron-emissive material 35, such as barium oxide. From their coils, the current leads 31, 32 extend lengthwise of the member 24 out from under the beryllia covering 33, and just outside it each of them is anchored to the member 24—as by a lashing of a couple of turns of (molybdenum) wire 36 with its ends 70 twisted together—to prevent any slight pull on 75

the lead from disturbing the covering 30. The upper electrode lead 31 is welded to another (molybdenum) lead wire 37, to which is also welded another lead 38 itself (electrically) connected to the emissive-coated tube 34 of the upper electrode 20. The lower electrode 20 has current leads 32, 39, likewise lashed and anchored to the member 24. The lower lead 32 of the upper electrode 20 and the upper lead 32 of the lower electrode 20 are directly connected, preferably by being in one continuous length, which is here shown as making about one and a half turns around the member 24 between the two electrodes. The lower lead 39 of the lower electrode 20 is welded to the stem lead 16, which extends up into the bulb 10 to one side of the member 20. The emissive-coated tube 34 of the lower electrode 20 is also connected to the stem lead 16 by a lead 41 welded to the latter.

20 While the resistance 22 and the discharge gap between the electrodes 20, 20 might be connected in parallel so far as the heating function of resistance 22 is concerned, there are important advantages in connecting them in series, which is accomplished by welding the lead wire 37 to the wire 25 already mentioned, as shown in Figs. 1 and 2. Thus the (tungsten) filament 22 ballasts the lamp, and may also increase the over-all resistance of the lamp so as to enable the lamp 30 to be operated on standard lighting circuits of around 110 to 120 volts. Assembly of the lamp as hereinafter described is easier if the wire 37 is somewhat flexible or even resilient between its connections to wires 31 and 25, which is facilitated by coiling this portion of wire 37 in a few large turns encircling wire 25.

In a lamp bulb of the type here shown, with a reduced neck 13 and a stem 14, it is difficult or impossible to bring the neck to the same temperature as the bulb proper, since the contracted space or "recess" in the neck tends (for various reasons) to run cool. As shown in Fig. 1, there is a loose-fitting glass shield 42, of inverted cup form, occluding the neck 13 about where it merges 40 or joins with the bulb proper, with a narrow but extended clearance or crack 43 around the shield, that will be closed by the (liquid) sodium or other working substance condensing in the clearance when the lamp is first operated for any 45 length of time. Thus the crack or joint at 43 is sealed and the neck recess is effectually shut off from the vapor space of the bulb 10, so that it cannot gradually entrap nearly all the metal in the lamp and leave the latter with an inadequate 50 atmosphere of metal vapor, as explained above. When this type of shut-off is used, the lamp should be charged with an excess of sodium or other metal as compared with ordinary practice, so that after formation of the seal at 43, there 55 may still be plenty of metal left for the normal operation of the lamp. The width of the clearance or crack at 43 should be great enough to insure against its being all taken up by temperature changes, so as to grip the shield 42 tight in the 60 neck 13 and perhaps burst the latter; and it should be small enough all around the shield to be in a practical way "capillary", so that a film of (liquid) metal cannot exist indefinitely on one or both walls of the clearance (the adjacent 65 shield and neck surfaces) without eventually touching the opposite wall all the way around. Subject to this last limitation, it need not, of course be uniform all around the shield, and the latter may even touch the surrounding wall at 70 one side. In general, a clearance of about 0.01

inch radial width, more or less, will be found satisfactory. As shown in Fig. 1, the shield 42 has an opening (in a central nipple 44) for the member 24, which may be tightly cemented therein as indicated at 45. The lead wire 16 extends through a small hole in the shield 42 and is cemented tightly therein as indicated at 46. On the lead wire 16 is shown (insulatively) mounted a hermetically sealed glass capsule 47 for containing a charge of vaporizable working substance. This capsule 47 may be encased in a short length of thin-walled (nickel) tubing 48 crimped in at the ends to retain the capsule.

In the manufacture of the lamp, the mount 11 with all the parts and their connections above described—including stem 14, leads 15, 16, capsule 47 (if used), members 24, shield 42, electrodes 20, and wire 25—is completed as shown in Fig. 1 before insertion in the lamp bulb 10, which at this time has a hollow "tubulature" 49 (like an exhaust tubulature) on its upper end, as indicated in dot and dash lines in Fig. 1. After inserting the mount 11 in the bulb 10 with the upper end of wire 25 in the tubulature 49, the latter may be fused off and sealed around the 25 wire 25 as shown in full lines; and then the stem 14 may be sealed into the neck 13 with the usual "pull-down" fused seal used in incandescent lamp manufacture. The pull-down thus given the mount 11 in sealing-in draws the finely-coiled 30 heating resistance filament 22 taut inside the tubular member 24, its coils stretching apart to permit any amount of pull-down required. The wire 37 will yield either to allow wire 25 to push into member 24 when the mount 11 is inserted in 35 bulb 10, or to permit the subsequent pull-down or both.

If the wire 25 is cemented or otherwise fixed tight in the upper end of the tubular member 24, with the filament 22 properly stretched therein, 40 the operation of fusing the wire 25 into the hollow (dot-and-dash) tubulature 49 will most naturally be deferred until after the stem 14 has been sealed into the neck 13 (with the usual pull-down seal). The fusing of wire 25 into tubulature 49 may also be thus postponed, if preferred, even when wire 25 is not cemented or otherwise fixed in the upper end of member 24.

After the lamp has been exhausted, it may be charged with neon or other gas through the exhaust tube 18 before sealing off. As a means of introducing a highly oxidizable working substance like sodium, the capsule 47 may be ruptured after the lamp has been exhausted (and preferably after it has been sealed off), thus liberating the sodium in the bulb 10. For this purpose, the metal-cased capsule 47 is brought into the field of a high-frequency coil externally surrounding the lamp 10 and the capsule is thus heated until the pressure of its contents due to 60 the heat generated in the metal casing 48 explodes or ruptures the capsule, which is softened by the heat. If the energy of the high frequency coil is powerful enough, the metal casing 48 may be dispensed with; although it is useful to retain the pieces of the ruptured capsule.

Fig. 3 illustrates a modified construction in which the heating resistance 22 extends through the electrodes 20, 20, and may assist in heating them. In this case also, therefore, the resistance 70 22 may extend with the electrodes 20, 20 substantially or approximately from end to end of the bulb (not shown), as pointed out in connection with Fig. 1.

In the operation of the device, starting "cold", 75

the current flows at first through the electrode-heating resistances 30, 30 and their interconnecting lead 32 and the envelope-heating resistance 22, in series; but as the electrodes 20, 20 heat up, 5 more and more current is carried by ions of the neon or other gas in the gap between them. As the whole lamp heats up and vaporizes some sodium or other metal, the metal ions participate in the luminous discharge—in shunt with the 10 resistances 30, 30 and lead 32. The lamp is internally heated by the filament resistance 22 as well as by the heat incident to the arc discharge (including that of the electrode-heaters 30, 30), and the member 24 absorbs heat from all these 15 sources and equalizes its distribution lengthwise of the envelope 10. There is also an automatic equalization due to the shunting of current away from the electrode heaters 30, 30 by the discharge as it increases. Thus the walls of the vapor 20 space are heated to substantially uniform temperature throughout their extent by coaction of the heater 22 with the discharge, assuring an adequate supply of metallic vapor for carrying the current of the luminous discharge, and giving 25 very much greater luminous efficiency than if the lamp had to be "forced" in order to vaporize the sodium entirely by the heat of the glow discharge.

As already stated, a sodium vapor lamp operates most efficiently at a temperature of about 250° C.; so that the less current has to be used in the glow discharge to maintain this temperature of the envelope, the better the lamp efficiency. Lamps constructed in accordance with 30 my invention operate at about 250° C. with a discharge energy consumption as low as about 0.1 or even 0.05 watt per square centimeter of envelope surface. While this gain in glow discharge efficiency is partly offset by the energy used in the (tungsten filament) heating resistances 22, which (especially with their coverings 24) are less efficient light producers than the discharge, the overall luminous efficiency is still very much improved by the heater.

45 While combination of the red-deficient yellow light from sodium vapor with that of a tungsten filament 22 would give a combined light of improved quality even with the filament bare because of the compensatory red emitted by the tungsten, the greater quantity of red emitted by the 50 ceramic (beryllia) tube 24 when heated by the filament suffices (when the parts are properly proportioned) to compensate substantially quantitatively for the red deficiency of the sodium glow, or, in other words, balances the yellow. By including a small compensatory amount of mercury with the sodium in the lamp, the yellow of the sodium can be balanced with the blue-green from the mercury, as well as with the red 55 from the tube 24, and a substantially or approximately white light thus produced. Whether this is done or not, more complete mixture of the different qualities or color tones of light from the glow discharge and from the heater (22, 24) can be obtained by enclosing the device in a light-diffusing globe, or by frosting the envelope 10, or by a combination of such measures. When the lamp is enclosed in a glass vacuum jacket to 60 reduce the loss of heat, as is commonly done with sodium vapor lamps, one or both walls of such jacket may be frosted or otherwise made diffusing.

The independent envelope-heating means need not necessarily be concentrated in a single axial heater as in Fig. 1, but may be divided into a plu-

rality of heaters, arranged or grouped around the envelope axis as evenly or symmetrically as may be. An initial step in such a division and distribution of heating means is illustrated by Fig. 4 where a group of two heaters similar to that of Fig. 1 are provided, each consisting of a filament 22 and a refractory tube 24 around it. These heaters are arranged symmetrically in the bulb 10, a short distance to either side of the bulb axis and of the electrodes 20a, 20a, and 10 extend in the direction of the electrode axis as in Fig. 1. The electrodes 20a, 20a occupy the same positions (axial and longitudinal) in the bulb as in Fig. 1, and are interconnected by an axial (molybdenum) current lead 32a. This lead 32a 15 may be supported at mid-length from the members 24, 24 by a bridge support comprising (molybdenum) wires 50, 50 wrapped around the members 24, 24 and fused into an insulative refractory (alumina) part 51 through which the lead 32a 20 extends. The lower electrode 20a is connected to the upper end of the stem lead 16, which extends up through a refractory insulating (alumina) tube or sleeve 24a in which it may be tightly cemented. The upper electrode 20a is connected 25 to the wire 25a sealed into the upper end of bulb 10. The members 24, 24 are mounted on the upper end of current leads 15a, 15a, and the heating filaments 22, 22 are connected between the upper ends of these leads 15a, 15a and the 30 lower ends of leads 25b, 25b that extend down into the upper ends of the members 24, 24. The shield 42a has nipple openings 44a, 44a in which the members 24, 24 may be tightly cemented, and thus affixed to the shield, or may be sealed by 35 metal condensation as in the clearance 43, and also a central nipple opening 42b in which the tube or sleeve 24a may be tightly cemented.

While various connections of the heating filaments 22, 22 with reference to the electrode discharge gap are possible—e. g., all in parallel or all 40 in series—I prefer to connect the filaments in parallel with one another and in series with the discharge gap. This is accomplished by welding both leads 15a, 15a to the stem lead 16 and welding 45 both leads 25b, 25b, to the wire 25a. As shown, the leads 25b, 25b are really "legs" of one U-bent wire whose mid-portion is welded to the wire 25a at the upper end of the upper electrode 20a.

In Fig. 4, the shield 42a not only forms part of 50 the mount 12, as in Fig. 1, but also serves as a means of holding the tubular supporting members 24, 24 in position relative to one another, and of mounting the lower electrode 20a in mid-position relative to them. This purpose, indeed, the shield 42a answers even more effectively and directly 55 than does the union of the leads 15a, 15a, 16 and 15 by welding and by the stem 14. Projecting inward from the shield 42a, the long, slender, members 24, 24 have their opposite ends held in proper 60 relation by the "spider" formed by the united wires 25b and 25a, which also serves as a means of mounting the upper electrode 20a in mid-position relative to the members 24, 24. The supporting members 24, 24 and their associated parts are 65 steadied in the envelope 10 by the attachment of the wire 25a to the envelope at 26, as in Fig. 1.

The construction of the electrodes 20a, 20a may be identical, but is somewhat different from the electrodes 20, 20 of Figs. 1 and 2, since they are not mounted around a supporting member 24. As shown in Fig. 5 each electrode 20a comprises a nickel tube 34a having secured in its end centrally bored, externally shouldered plugs 33a, 33a, of refractory material, such as lava. The tube 34a 70

has an external coating 35 of electron-emissive material.

In the central holes in the plugs 33a, 33a are (nickel) current leads—31a, 32b for the upper electrode 20a; and 32b, 39a for the lower electrode 20a—and between these leads are connected a heating resistance 30a such as a finely coiled tungsten filament. The tube 34a is (electrically) connected to the lead 31a (or 39a) by a conductive 5 (nickel) strip 38a. The lead 31a is welded to the wire 25a, the lead 39a to the stem lead 16 and the leads 32b to opposite ends of the lead 32a. In operation, the glow discharge between the electrodes 20a, 20a is in parallel with the electrode-10 heating resistances 30a, 30a.

The electric circuits and connections of the lamp shown in Fig. 4 are diagrammatically illustrated in Fig. 5, and marked with the same reference characters as in the foregoing description.

20 Various parts and features shown in Figs. 4, 5, and 6 are marked with the same reference numerals as the corresponding ones in Figs. 1, 2, and 3 (with a subscript letter where distinction appears desirable), as a means of dispensing with repetitive description; and it will be understood that the same materials may be used with corresponding parts in Figs. 4, 5, and 6 as in Figs. 1, 2, and 3, except as otherwise indicated above. The operation of the lamp shown in Figs. 4, 5, and 6 25 is similar to the lamp of Figs. 1, 2, and 3, and the same remarks apply as regards balance of color tones of light from the arc discharge and the heater, use of mercury with sodium, use of frosting or other light-diffusing means and of a vacuum 30 jacket, etc.

Figs. 7, 8, 9, and 10 illustrate particular advantages of multiplying the heaters or ballasts, and of using an odd number—three in the present instance—grouped around the electrodes 20a, 20a 40 in their midst, each consisting of an insulative refractory tubular member 24 and a (tungsten) heating and ballast filament 22 within it. The particular advantage of the odd number of ballasts 22 is that all can be connected in series with the electrode gap, thus allowing a heavier and more durable wire to be used for the resistance elements 22 because of the increased length which is permitted. As the number of heaters is increased, also, the uniformity of envelope heating given by 45 50 a single axial heater (Fig. 1) is more and more nearly approximated.

Dispensing with repetitive description by the use of the same reference characters as in Figs. 1, 4, 5, and 6 to indicate corresponding parts and 55 features—with distinctive letters where distinction appears necessary—it may be noted that in Figs. 7 and 8 the function of holding the parts in proper relative position performed by the shield 42b at the lower end of the mount 11 (Figs. 7 and 9) is performed at its upper end by a three-armed spider formed by fusing into a button 55 of insulative refractory material (alumina) an inserted U-wire 25c, (which has its horizontal member bent 120° in a horizontal plane); a wire 25d, which is bent to an (inverted) L-shape; and an axial wire 25e, which extends right through the button 55. The button 55 insulates the wires 25c, 25d and 25e, from one another. The arms of the wire 25c are covered with insulating sleeves 56, to prevent any electrical discharge between them and the upper electrode 20a; and the ends of these sleeves are cemented to those of tubes 24, 24 and to button 55 60 with insulative cement 57, for the same purpose. The upper electrode 20a is connected to wire 25e, which is in turn connected to wire 25d by a wire 70

37b welded to wires 25d and 25e. The upper end of the mount may be steadied by attaching the wire 25e to the bulb 10 at 26 as in Figs. 1 and 4. The electrical connection of the three filaments 22 in series with one another and with the electrodes 20a, 20a by the wires 15, 25c, 16b, 25e, 37b, 25d, and 16 and the connections of the electrode-heating resistances 30, 30, will all be readily understood from the wiring diagram in Fig. 10 when examined in connection with Fig. 5. It is to be 10 noted that the electrode gap (and the lead 32a) are interposed between two directly interconnected resistances 22 and the third resistance 22, so that the difference of potential between each electrode and the resistances 22 is less than if the three 15 resistances 22 were all directly connected in a "string", and this "string" as a unit were connected in series with the electrode gap.

What I claim as new and desire to secure by Letters Patent of the United States, is:

20 1. A vapor lamp comprising an envelope with electron-emissive electrodes therein; a charge of vaporizable working substance in said envelope producing only a small vapor pressure therein during operation of the lamp; and a single walled 25 luminous tube enclosing a heating resistance and ballast means in the vapor space of said envelope, a heating resistance surrounded by one of said electrodes, a current lead external to said tube and connecting said heating resistance in shunt 30 with the discharge path between said electrodes, said resistance and ballast means being connected in series with said heating resistance and the electrode gap and heating said tube to luminosity, said tube being directly exposed to the 35 luminous vapor space and being adapted and arranged to heat the walls of said space to substantially uniform temperature sufficient to maintain an adequate atmosphere of the metal vapor throughout said space, and emitting light 40 of color tone such as to compensate for color deficiency of the gaseous electric discharge when said lamp is at equilibrium.

2. A vapor lamp comprising an envelope with electron-emissive electrodes therein; a charge of vaporizable working substance in said envelope producing only a small vapor pressure therein during operation of the lamp; and a single walled tube enclosing a heating resistance and ballast means in the vapor space of said envelope, a heating resistance surrounded by one of said electrodes, a current lead external to said tube and connecting said heating resistance in shunt with the discharge path between said electrodes, said resistance and ballast means being connected in 45 series with said heating resistance and the electrode gap and heating said tube to luminosity, said tube being directly exposed to the luminous vapor space and being adapted and arranged to be luminous when said lamp is at equilibrium and to heat the walls of said space to substantially uniform temperature sufficient to maintain an adequate atmosphere of the metal vapor throughout said space, and having such resistance, relative to the operating resistance across the electrode gap, that the device can operate on ordinary standard lighting voltages.

3. A vapor lamp comprising an elongated envelope with electron-emissive electrodes in its ends; a charge of vaporizable working substance in said envelope, producing only a small vapor pressure therein during operation of the lamp; and a single walled tube enclosing a heating resistance and ballast means in the vapor space of said envelope, a heating resistance surrounded 70 75

by one of said electrodes, a current lead external to said tube and connecting said heating resistance in shunt with the discharge path between said electrodes, said resistance and ballast means being connected in series with said heating resistance and the electrode gap and extending, with the electrodes, axially of the envelope approximately from end to end of the vapor space, so as to heat the walls of said space to substantially uniform temperature sufficient to maintain an adequate atmosphere of the metal vapor throughout said space, said tube being heated to luminosity by said resistance when said lamp is at equilibrium and being directly exposed to the luminous vapor space.

4. An operating assembly for a device of the character described comprising cooperating coaxial diffuse-discharge electrodes; means for mounting said electrodes with a discharge gap between them consisting of a single walled refractory insulative tubular supporting means extending in the direction of the electrode axes; a heating resistance wrapped around said tubular support means and interposed between said support means and one of said electrodes, a current lead outside of said tubular support means and connecting said resistance in shunt with the discharge path between said electrodes; and resistance means in said tubular means connected in series with said heating resistance and with the electrode gap.

5. An operating assembly for a device of the character described comprising cooperating coaxial diffuse-discharge electrodes; means for mounting said electrodes in a bulb, with a discharge gap between them, including a shield for occluding the base end or neck of the bulb, refractory insulative tubular supporting means affixed to and projecting from said shield and supporting means affixed to said tubular supporting means and fused into said bulb; a current lead interconnecting said electrodes; and resistance means in said tubular means connected in series with the electrode gap.

6. An operating assembly for a device of the character described consisting of a group of symmetrically arranged substantially parallel refractory insulative tubes; one of said tubes being in contact with two of the other tubes, means at opposite ends of said tubes for holding them in position relative to one another; cooperating diffuse-discharge electrodes mounted on said means in the midst of the group of tubes, at opposite ends thereof, a heating resistance mounted in said electrodes and a current lead outside of said tubes and connecting said heating resistances in shunt to the discharge path between said electrodes; and resistances in said tubes connected in series with said heating resistances and the electrode gap.

GEORGE E. INMAN. 30
